UNITED STATES PATENT OFFICE.

THOMAS I. COCHRAN, OF DETROIT, MICHIGAN.

FUEL-FEEDING APPARATUS FOR INTERNAL-COMBUSTION ENGINES.

1,256,519.

Specification of Letters Patent. Patented Feb. 19, 1913.

Application filed December 21, 1912. Serial No. 138,252.

To all whom it may concern:

Be it known that I, THOMAS I. COCHRAN, a citizen of the United States, residing at Detroit, county of Wayne, State of Michigan, have invented a certain new and useful Improvement in Fuel-Feeding Apparatus for Internal-Combustion Engines, and declare the following to be a full, clear, and exact description of the same, such as will enable others skilled in the art to which it pertains to make and use the same, reference being had to the accompanying drawings, which form a part of this specification.

This invention relates to fuel-feeding apparatus for internal combustion engines, and has for its object an improved construction whereby the quantity of gasoline or other liquid fuel supplied to the carburetor from the main supply tank is kept substantially constant, whether the vehicle be running on a level, on a laterally slanting road, up hill, or down hill; thus there is avoided either the flooding of the carburetor or the feeding to it of an insufficient supply of gasoline. The device is adapted and in fact designed to respond unusually quickly to the various running conditions which are ordinarily encountered.

In the drawings:

30 Figure 1 is a vertical sectional elevation of my improved construction.

Fig. 2 is a plan view of the top portion of the casing, the relative position of certain of the parts being shown in dotted lines.

35 Fig. 3 is a vertical sectional view of a slightly modified form of suction valve, and of the adjacent portions of the casing.

Fig. 4 is a vertical sectional elevation of another modification, in which the suction valve and air vent are located directly above the float which actuates them.

In Fig. 1, A represents the shell or casing of the device, which is separated by a diaphragm B into the lower chamber C and upper chamber D; these are connected by the pipe E, and the orifice E' in the diaphragm, and at the bottom of the pipe E is located a check valve of any suitable type, designed to be closed by suction, such for example as the ball F, seating in the tapering outlet portion F' of the pipe E, and being held from falling out, when not sucked onto its seat, by the pin or bar F''. From the upper portion of this lower chamber C rises the air inlet pipe G.

The gasoline inlet for the upper chamber

D may be located in any desired part of the upper portion of the chamber; in Fig. 1 it is shown at I. Rising through the central portion of the upper chamber D is a guide-tube H over which the central pipe K of the float J slidably engages. The upper portion of the pipe K is slotted as at K', and through it engages the free end of the lever L, which is pivoted at L' to the shell M of the suction valve. The piston or plunger N of the suction valve is connected with the forked end of the lever L by means of the pin O, and the valve as a whole is connected with the engine manifold by means of the threaded terminal P. Below the lower end of the piston N, when the same is in raised position, is the suction port R, which so counteracts any suction effect from the manifold upon the piston N, that it is almost negligible until after the piston has been positively depressed by the raising of the lever L by the float J, as hereinafter described; after the plunger N has covered the suction port R, however, the seating action of the plunger is quick and sharp.

The air valve S in the upper portion of the shell is preferably located so that its bore U is directly above the lever L. When the lever L is in lowered position, the stem 85 T, whose lower end is attached to the lever L intermediate its end and its point of pivoting, extends upwardly and slidably engages in the bore T but not far enough to displace the ball V from its seat V'. When, 90 however, the lever L is raised, the ball V is unseated, permitting air to enter the chamber D, to counteract the vacuum effect caused by the engine suction through the valve M.

95 The operation of this device is as follows: Gasolene is admitted to the shell A through the gasoline inlet I from the storage tank, which is generally located in the rear of the vehicle. As long as there is no suction from the engine manifold, the gasoline passes through the pipe E and past the unseated ball valve F. When this is filled, or when suction begins from the engine manifold, the ball valve F is drawn 100 to position of closure over the end of the pipe E, and instead of falling into the lower chamber C of the shell, gasoline begins to accumulate in the upper chamber D, finally causing the float J to rise. The 105 slotted pipe K, on the upper part of the float J engages the lever L, with its lower

edge K^3 though only after the float has risen appreciably, and thereafter tends to slowly depress the piston N and raise the stem T leading to the air valve. As soon as the piston is depressed enough to effect the closure of the suction port R , the suction of the engine manifold immediately becomes so great as to draw the piston N the rest of the way down quickly and sharply. This in turn forces the stem T against the ball V of the air valve S , thus unseating it and exposing the interior of the upper chamber D to atmospheric pressure. This last quick pull upon the plunger N also results in raising the free end of the lever L above the lower edge K^3 of the slot in the pipe K . The exposure of the interior of the upper chamber D to atmospheric pressure in turn ends the suction pull on the ball valve F , at the base of the pipe E , allowing the gasoline in the upper chamber D to resume flowing therethrough, and consequently allowing the float J to fall once more. Due to the slotting of the pipe K , the first portion of the fall of the float does not affect the lever, just as the first portion of its rising movement does not raise the lever L . When, however, the upper edge K^2 of the slot in the pipe K encounters the lever L , it first draws the free end thereof downwardly as slowly as the gasoline level in the upper chamber D is dropping. At the same time that the valve member N is being raised by the dropping of the lever L , the stem T of the air valve, whose lower end is pivoted to the lever L , is also being drawn down, enabling the ball V to seat, thus closing the air valve S . A slight further downward movement of the lever L and consequent raising of the valve piston N results in the uncovering of the suction port R , thus causing a resumption of the suction influence from the engine manifold upon the interior of the upper chamber D , and consequently upon the ball valve F at the lower end of the pipe E .

In Fig. 3 I have shown a somewhat modified construction, in which the functions of the suction valve and air valve are united in one shell. In place of the separate air valve S and its actuating stem T , I provide a thicker side wall for the suction valve shell M ; through it extends a bore Y , leading to the outer air in the same manner as the valve S of Fig. 1. The upper end of the bore or air port Y is closed by the plunger N when that member is in raised position and the outer or free end of the lever L is in lowered position, in the same manner that the stem T falls short of unseating the ball V (Fig. 1). But as soon as the gradual raising of the free end of the lever L operates to depress the piston N enough to cover the port R , the resultant strong suction

makes the rest of its movement practically instantaneous.

In Fig. 4, the suction valve and vent port are located in line with the upwardly extended vertical axis of the central guide tube H and of the float J . In this form, the lever is of the intermediately pivoted type, shown at W ; the weight W' tends to make the opposite end of the lever follow the upward travel of the cross-bar W^2 , its most important function being the holding up of the sleeve Z , after it has been raised so as to cover the port Z' until the fall of the float, because of the drop in the gasoline level, pulls it down, overcoming the weight of W' . With the sleeve Z in closure position over the port Z' , the resultant strong suction then acts, on the same principle as before, to draw the plunger X upward with a quick movement, thus exposing the lower end of the air vent X' and breaking the suction on the lower end of the pipe E in the lower chamber C ; the resultant drop in the gasoline level and consequently in the position of the float J effects the dropping of the vertical stem W^2 and its cross-bar Z^2 , thus permitting the slow uncovering of the suction vent Z' , because the sleeve Z is no longer held up by the cross-bar Z^2 . The further drop of the piston X serves to close the air vent passage X' .

What I claim is:—

1. In a fuel supply apparatus for internal combustion engines, in combination with a plurality of apertured casing, a communication to a suction source, provided with a suction port, connected with one of the apertures, a valve adapted to control said communication and to close and open the suction port therein by its movement toward and away from its seat, an air valve adapted to control another of the apertures in the casing, a lever member with which each of said valves is operatively connected and by whose pull the initial closing and opening movements of said first named valve are brought about to effect the closure and opening of the suction port, and a float member with which the free end of said lever has a slip connection, whereby the initial movements thereof and consequently of its connected valve members in either direction are dependent upon the rise and fall of the float with the gasoline level, after which the lever is free to move independently of the float in response to the pull of said first named valve due to the changed suction conditions within the casing resulting from its closure or opening of the suction port. 125

2. In combination with a casing having a plurality of apertures, a float therein, a communication between one of the apertures in the casing and a suction source, a normally open suction port in said communica- 130

tion, a valve member adapted to control said communication and to close said suction port when in intermediate position with respect to its controlling seat for said communication, a pivoted lever member, operatively connected with said valve member and having a slip connection with said float, whereby the initial actuation of said valve to such intermediate position is dependent on the 10 movement of the float, and an air valve adapted to be closed by the downward movement of the lever when actuated by the fall of the float with the gasoline level and to be opened by the final suction-induced movement 15 of the suction valve member and consequently of its connected lever after its initial movement has resulted in the closing of the suction port.

3. The combination of a casing having a 20 plurality of apertures, a communication to a suction source having a normally open suction port, a valve for controlling said communication and for closing and opening said suction port, before reaching its fully closed 25 and open positions with respect to said communication, a normally closed air valve appurtenant to another of the apertures in the casing, a float within the casing, and a pivoted lever member operatively connected with 30 said valve members and having a loose connection with said float, whereby the initial closing and opening movements of said first named valve, resulting in the closure and opening of the suction port, are communicated to it by the lever when actuated by the rise and fall of the float with the gasoline level, the later movements of said valves and of said connected lever being dependent upon the changed suction conditions within 35 the casing due to the closure or opening of the suction port and of the air valve.

4. A fuel supply apparatus for internal combustion engines, having in combination with a shell, a connection to the engine manifold, a valve controlling said connection, a suction port adapted to be closed and opened by the initial closing and opening movements of said valve, a lever connected with said valve and having a heavy free end 45 whereby said valve is held normally open, a float having a loose connection with said lever, whereby said lever and thereby said valve is actuated by the rise and fall of the float only during the early stage of its movement in either direction, the subsequent portion 55 of its cycle of movement being effected by the changed suction conditions upon said suction valve due to the closure and opening of said suction port, and an air valve 60 adapted to be opened and closed by the final movement of said lever in either direction.

5. In a fuel supply apparatus for internal combustion engines, the combination of a 65 casing having inlet and outlet apertures, a

float member, a pivoted lever having a loose connection with said float member, whereby the lever derives its primary actuation in either direction from the movement of said float member according to the gasoline level, 70 a communication from said outlet aperture to a suction source, a valve controlling the flow through said outlet aperture, said valve being operatively connected with said lever, a normally open suction port adapted to be 75 closed and opened by the initial closing and opening movements of said valve induced by the float-actuated movement of said lever, the final movement in either direction following from the changed suction conditions 80 due to the closure and opening respectively of said suction port, and a normally closed air valve adapted to be opened and closed by the final suction-influenced movement of 85 said lever.

6. In a fuel supply apparatus for internal-combustion engines, in combination with a casing having inlet and outlet apertures, said outlet aperture being provided with a suction port, a valve for controlling the 90 flow through said outlet aperture when in fully seated and for contemporaneously controlling said suction port when in intermediate position with respect to its seat, a lever member operatively connected with said 95 valve, a float member within said casing, with which said lever member has a loose connection, whereby the actuation of the lever member in either direction and the consequent closing and opening of said suction 100 port by said valve is dependent upon the communicated upward and downward movement of the float against the lever, and whereby the subsequent movement of the 105 lever is regulated by the changed conditions of suction within the casing due to the closure and opening of the suction port by the lever-actuated movement of the valve with respect thereto.

7. In combination with a casing having a pair of connected chambers, a float in the upper one of said chambers, a communication to a suction source from said upper chamber, a valve adapted to control said communication, a normally open suction vent 110 adapted to be closed and opened by the primary movement of said valve toward its position of full closure and opening respectively, a lever operatively connected with said valve and deriving its primary actuation in each direction from the movement of said float, whereby said valve is actuated to a degree sufficient to effect such closure and opening of said suction vent, and a normally closed air valve adapted to be opened at 115 closed by the suction-influenced later movement of said lever when its float-controlled 120 movement has resulted in the closure and opening respectively of said suction vent.

8. The combination, with an apertured 125

shell member containing an upper chamber and a lower chamber, of a valve-controlled communication between said chambers, a communication between one of the apertures in the shell and a suction source, a valve member controlling said communication, a normally open suction vent connected with said communication and adapted to be closed and opened by the initial movement 10 of the valve toward and away from its seat, a float in said upper chamber, and a lever member, operatively connected with said valve and deriving its primary movement in either direction from said float.

15 9. A suction valve mechanism for fuel-feeding apparatus, comprising a shell provided with an engine manifold connection and an appurtenant suction port, a valve member adapted to control the manifold connection when in seated position and to close said suction port previous to its seating and to still be in position of closure thereover after its movement away from its seated position has begun, and a float-actuated 20 lever member operatively connected with said valve, adapted to initially actuate said valve toward and away from its seat to an extent sufficient to respectively open and close the suction port, the connection of 25 said lever with the float being such that after such opening and closing of the suction port has been accomplished, the valve and its connected lever are free to respond to the changed suction conditions within the shell resulting from the closure and opening 30

of the suction port, and a normally closed air valve adapted to be opened and closed by the suction-influenced later movement of said lever and suction valve.

10. In combination with an apertured 40 casing, a communication between one of the apertures and a suction source, said communication having a suction port, a valve controlling said communication and the suction port, said suction port being adapted 45 to be blanked and uncovered by the initial movement of said valve toward closing and opening positions respectively with respect to said communication, an air port adapted to be opened and closed coincidently with 50 the movement of the valve, a float within said casing, and a lever member for actuating said valve in the initial stages of its opening and closing movements, said lever member having a slip connection with said 55 float whereby it is actuated thereby sufficiently in either direction to positively effect the blanking and uncovering respectively of the suction port, after which the 60 final closure and opening movements of said valve are determined independently thereof by the changed suction conditions within the casing due to the blanking or the uncovering of the suction port.

In testimony whereof, I sign this specification in the presence of two witnesses.

THOMAS I. COCHRAN.
